United States Patent Office

Des. 229,928

Patented Jan. 15, 1974

229,928

SNOWMOBILE

Y. Anselme Lapointe and Thomas Scott, Valcourt, Quebec, Canada, assignors to Bombardier Limited, Valcourt, Quebec, Canada

Filed May 10, 1972, Ser. No. 252,161

Term of patent 14 years

Int. Cl. D12—14

U.S. Cl. D14—24

FIG. 2

FIG. 3

FIG. 4

FIG. 5

FIG. 1 is a perspective view of a snowmobile from the front and one side, showing our new design;

FIG. 2 is a side elevational view thereof;

FIG. 3 is a top plan view thereof;

FIG. 4 is a front elevational view thereof; and

FIG. 5 is a rear elevational view thereof.

The undisclosed side is the same in appearance as the side shown.

We claim:

The ornamental design for a snowmobile, as shown and described.
